UNITED STATES PATENT OFFICE.

CHARLES M. BROWN, OF CHICAGO, ILLINOIS.

PROJECTILE.

SPECIFICATION forming part of Letters Patent No. 656,934, dated August 28, 1900.

Application filed January 22, 1900. Serial No. 2,320. (No model.)

To all whom it may concern:

Be it known that I, CHARLES M. BROWN, a citizen of the United States, residing at Chicago, in the county of Cook and State of Illinois, have invented certain new and useful Improvements in Projectiles, of which the following is a specification.

The present invention relates to that class of projectiles that are provided with a vane or tailpiece adapted to control the position of the projectile during its flight and compel it to travel at all times point foremost.

The object of the invention is to provide an improved projectile of this class; and to this end the invention consists in the features of novelty that are hereinafter described with reference to the accompanying drawings, which are made a part hereof, and in which—

Figure 1 is a longitudinal section of a projectile embodying the invention, the parts being shown in the positions that they occupy before the projectile is fired. Fig. 2 is a longitudinal section of the rear end of said projectile, the parts being shown in the positions that they occupy during the flight of the projectile. Fig. 3 is a section on the line 3-3, Fig. 1. Fig. 4 is an elevation of the rear end of the projectile.

A represents the body of the projectile, which in the illustration which I have selected for the purposes of the present application is in the form of a hollow shell having a chamber B for containing an explosive charge. The rear end of this chamber is closed by a screw-plug C, having a centrally-located threaded opening C' for receiving the fuse. This plug also provides the means for attaching the vane or tailpiece D, which according to the present invention consists of a ring or a disk having a central opening d, registering with the fuse-opening C' of the plug C. The plug is provided with a plurality of equidistant sockets E, which project inward a considerable distance past the inner end of the plug proper and are adapted to receive the enlarged heads f of the stems F, by which the vane or tailpiece is carried. The object of the prolongation of the sockets E is to enable the use of stems of the length necessary in order to permit the tailpiece to move a sufficient distance away from the rear end of the projectile. The inner end of each of the

sockets E is closed by a screw-plug e. The plug C has a flange c, which bears against the rear end of the body proper, and this flange is reduced for the purpose of allowing the air to impinge against the margin of the vane or tailpiece during the flight of the projectile, and thus move the vane or tailpiece from its position against the rear end of the projectile, as shown in Fig. 1, to its position some distance in rear thereof, as shown in Fig. 2. The margin of the vane or tailpiece is also chamfered on the forward side. As a result of this the air impinging upon the sloping portion of the vane is deflected outward, and thereby tends to more certainly hold the vane in correct position at the rear of the projectile. It is thought that by sufficiently reducing the projectile in the vicinity of the vane or tailpiece the action of the air will be sufficient to displace the vane or tailpiece in the manner described. I have not, however, verified this by tests, and while reserving to myself the right to use this means alone for displacing the vane or tailpiece, should it prove to be efficient to this end, still I have shown in the drawings an additional means by which the vane or tailpiece will with certainty be displaced. This additional means consists of one or more chambers G, formed in the rear end of the plug C and filled with a slow-burning explosive substance, the vane or tailpiece being provided opposite each of said chambers with an opening d'. The heat produced by the explosion of the projecting charge ignites the charge in the chambers G through the openings d', and by reason of the character of the explosive in these chambers G its complete explosion will not take place until after the projecting force due to the explosion of the projecting charge has ceased to act upon the vane or tailpiece. This remaining unexploded portion of the charges in the chambers G will then in exploding produce a backward pressure upon the vane or tailpiece around the margins of the openings d', which are smaller than the openings to the chambers G, and displace it in the manner described. Preferably I use a plurality of these chambers G, and dispose them at equal distances apart in order to preserve the balanced condition of the projectile. It is for this reason also that I prefer to use a

vane or tailpiece of the annular form shown, which form enables the use of a centrally-disposed fuse.

In order to hold the vane or tailpiece in position against the rear end of the projectile and prevent it from moving away therefrom in the ordinary handling of the projectile, I unite the adjacent faces of the vane or tailpiece and projectile by some holding means, the holding power of which will be destroyed by the heat developed in the explosion of the projecting charge. To this end I prefer to interpose between said surfaces an adhesive gasket H, made of or containing an adhesive cement or a thin film of soft solder which will melt readily by the heat developed.

I have shown and described the several features of my invention as being embodied in a hollow shell; but manifestly many of its features are not limited to shells of this class.

I am aware that it has been proposed to provide a projectile with a vane or tailpiece consisting of a continuous disk which is practically equal in diameter with the diameter 25 of the plug for closing the rear end of the projectile, the margin of the plug in the immediate vicinity of the vane or tailpiece being gradually contracted. This contraction of the plug is not the equivalent of chamfering the vane or tailpiece, nor is a vane or tailpiece consisting of the continuous disk the equivalent of a vane or tailpiece consisting of a disk having an opening through it. The advantages of the chamfer at the outer 35 edge of the vane or tailpiece are that it not only tends to hold the projectile to its course in the manner already described, but in addition to this it tends to augment the effect of the vane or tailpiece in returning the projectile to a position strictly in line with its trajectory should it swerve therefrom. The reason for this is that while the projectile remains strictly in line with its trajectory the currents of air striking the chamfered surface will be deflected outward, so that so long as these currents remain equal on all 40 sides of the vane or tailpiece they will tend to hold the projectile to its course; but should the projectile from any cause be swerved from 45 a position strictly in line with its trajectory then the chamfered surface on one side of the vane or tailpiece will be brought to a position more nearly perpendicular to the line of resistance, while the chamfered surface on 50 the opposite side of the vane or tailpiece will be brought to a position more nearly parallel with this line. The advantage of a vane or tailpiece having an opening is that the opening affords an exit for the air which enters 55 the space between the vane or tailpiece and the body. Without any opening in the vane or tailpiece the air would be compelled to both enter and leave this space at the periphery of the vane or tailpiece, and this would 60 result in more or less inequality in the distribution of the pressure.

Having described my invention, what I

claim as new, and desire to secure by Letters Patent, is—

1. A projectile having a body, a vane or tailpiece consisting of a disk adapted to seat against the rear end of the body, and means for connecting the vane or tailpiece with the body and allowing the vane or tailpiece to move a limited distance in rear thereof, the outer margin of the vane or tailpiece being chamfered, substantially as set forth.

2. A projectile having a body, a vane or tailpiece, a chamber in one of them, means for developing pressure in said chamber for displacing the vane or tailpiece after the projectile leaves the gun, and means for connecting the vane or tailpiece with the body and permitting it to move a limited distance in rear thereof, substantially as set forth.

3. A projectile having a body, a vane or tailpiece adapted to seat against the rear end of the body, means for connecting the vane or tailpiece with the body and allowing the vane or tailpiece to move a limited distance in rear thereof, and a chamber adapted to contain an explosive charge for moving the vane or tailpiece away from the body, substantially as set forth.

4. A projectile having a body, a vane or tailpiece, means for connecting the vane or tailpiece with the body and permitting it to move a limited distance in rear thereof, the body being provided with a chamber for containing an explosive charge which when fired will exert pressure upon the vane or tailpiece and move it away from the body, substantially as set forth.

5. A projectile having a body, a vane or tailpiece adapted to seat against the rear of the body, means for connecting the vane or tailpiece with the body and permitting it to move a limited distance in rear thereof, the body being provided with a chamber adapted to contain an explosive charge and the vane or tailpiece being provided with an opening through which said charge is ignited by the explosion of the projecting charge, substantially as set forth.

6. A projectile having a body, a vane or tailpiece in the nature of a disk adapted to seat against the rear end of the body, said vane or tailpiece having an opening for the passage of air, and means for connecting the vane or tailpiece with the body and permitting it to move a limited distance in rear thereof, substantially as set forth.

7. A projectile having a body, a vane or tailpiece adapted to seat against the rear of the body, said vane or tailpiece consisting of an annular disk or ring, and means for connecting the vane or tailpiece with the body and permitting it to move a limited distance in rear thereof, substantially as set forth.

8. A projectile having a body provided with a charge-chamber, a centrally-located fuse-opening at the rear end of the body, a vane or tailpiece consisting of an annular disk, the central opening of which registers with the

fuse-opening aforesaid, and means for connecting said vane or tailpiece with the body and permitting it to move a limited distance in rear thereof, substantially as set forth.

5 9. A projectile having a body provided with a charge-chamber and a plug closing the rear end of said chamber, said plug having a centrally-located fuse-opening, a vane or tailpiece consisting of an annular disk, the central opening of which registers with the fuse-opening aforesaid, and means for connecting said vane or tailpiece with the body and permitting it to move a limited distance in rear thereof, substantially as set forth.

10 15. A projectile having a body, a tailpiece adapted to seat against the rear end of the body, means for connecting the tailpiece with the body and permitting it to move a limited distance in rear thereof, and means for holding the tailpiece against the rear end of the

body before it is fired, said holding means being such that its holding power is destroyed by the heat generated by the explosion of the projecting charge, substantially as set forth.

11. A projectile having a body, a vane or tailpiece adapted to seat against the rear end thereof, means for connecting the vane or tailpiece with the body and permitting it to move a limited distance in rear thereof, and an adhesive substance uniting the vane or tailpiece and the body, said adhesive substance being such that its holding power is destroyed by the heat developed in the explosion of the projecting charge, substantially as set forth.
